UNITED STATES PATENT OFFICE.

CHARLES HERSCHEL KOYL, OF EASTON, PENNSYLVANIA.

CAR-ROOF.

SPECIFICATION forming part of Letters Patent No. 436,361, dated September 16, 1890.

Application filed January 30, 1890. Serial No. 338,678. (No model.)

To all whom it may concern:

Be it known that I, CHARLES HERSCHEL KOYL, of Easton, in the State of Pennsylvania, have invented a new and useful Improvement 5 in Car-Roofs, of which the following is a specification.

My invention is designed to improve the interior lighting of railway-cars and like structures. Under the plan at present in 10 vogue, in which lights, whether gas-burners, electric lamps, or oil-lamps, are usually strung along the car at intervals in the line of the longitudinal center of the car and at a short 15 distance below the ceiling, or that portion of it which is formed by the central raised portion of the car-roof, much of the light from the burners or lamps is lost in the ceiling, and from this and other causes the car is usually 20 insufficiently lighted, to the consequent discomfort of the passengers. To remedy this defect I make the car-roof, or at least the interior face of the car, parabolic or approximately parabolic in cross-section. This parabolic contour may, if desired, be given to the 25 whole of the ceiling from side to side of the car; but in practice I have found it sufficient to confine this shape to the dome or central raised portion of the roof, under which the 30 lamps or burners are commonly placed, and this latter plan I prefer. The parabolic shape imparted to the ceiling is crosswise of the car. I do not care for any longitudinal curvature 35 of this character. The object is to reflect in the direction of passengers the light which would otherwise be lost in the ceiling, and for this purpose only the crosswise parabolic curvature is essential. In conjunction with a roof of this shape I employ lamps or illuminating-burners, which are placed at intervals 40 apart at the focal distance from the ceiling—that is to say, in the line of the foci of the parabolic curves which give the contour to the ceiling. It is in this combination of a car roof or ceiling, parabolic or approximately 45 so in section, with lights located at focal distance therefrom, that my invention essentially is comprised. Under this arrangement the reflected rays are substantially parallel

with one another, and are thrown directly down upon the passengers, and in this way I 50 find that with the same lamps the amount of light available for passengers is about double that which is available when the ordinary car ceiling or roof is employed. The parabolic surface of the ceiling is of course so made as 55 to be a reflector, and I prefer that this surface should be slightly corrugated, as indicated, for example, in my Letters Patent No. 410,598, of September 10, 1889. The character of the lining of the roof which furnishes 60 the reflecting-surface is, however, immaterial. A plain white lining of any suitable material answers very well.

In the accompanying drawing I have illustrated a cross-section of the body of a car containing my invention, that portion of the interior of the car beyond the plane of section being shown in perspective. In this case the parabolic curvature is confined to the interior of the dome or raised central portion A of the 70 car-roof. The interior surface or ceiling of this portion of the roof is parabolic, or approximately so, in cross-section, as shown by the curve a. There is no longitudinal curvature to it. In the line of the foci of the innumerable parabolic curves which make up the ceiling are placed, at suitable intervals apart, the incandescent or other lamps B, the light-giving portion of the lamps being at 75 focal distance from the ceiling, this focal distance being determined by the aid of well-known formulæ. Under this arrangement the upward rays from the lamps, which otherwise would be lost in the ceiling, are, as indicated by the dotted lines, reflected downward nearly in parallelism, and in such manner as to aid materially the direct downward rays, and, as before said, to about double the 80 light available for passengers.

Having now described my invention and 90 the manner in which the same is or may be carried into effect, what I claim, and desire to secure by Letters Patent, is—

1. A car-roof the interior surface or ceiling of which is formed as a reflecting-surface of 95 parabolic shape, or approximately so, in cross-

section, or crosswise of the car only, substantially as and for the purposes hereinbefore set forth.

2. A car-roof the interior surface or ceiling 5 of which is formed as a reflecting-surface of parabolic shape, or approximately so, in cross-section, or crosswise of the car only, in combination with lamps or burners located at

focal distances therefrom, substantially as and for the purposes hereinbefore set forth. 10

In testimony whereof I have hereunto set my hand this 28th day of January, 1890.

CHARLES HERSCHEL KOYL.
